(57) **CLAIM**

The ornamental design for a liquid containment device plug, as shown and described.

DESCRIPTION

FIG. 1 is a perspective view of a new design for a plug that seals a liquid containment device.

FIG. 2 is a top view thereof;

FIG. 3 is a bottom view thereof;

FIG. 4 is a front view thereof;

FIG. 5 is a rear view thereof; and,

FIG. 6 is a left side view, the right side view being a mirror image thereof.

The broken line showing of portions of the liquid containment device plug is included for the purpose of illustrating and forms no part of the claimed design.
